(57) **CLAIM**

The ornamental design for audio equipment, as shown and described.

DESCRIPTION

FIG. 1 is a top, left, front perspective view of audio equipment, showing our new design;

FIG. 2 is a top, right, front perspective view thereof;

FIG. 3 is a top, front perspective view thereof;

FIG. 4 is a top, plan view thereof;

FIG. 5 is a bottom plan view thereof;

FIG. 6 is a left side elevation view thereof;

FIG. 7 is a right side elevation view thereof; and,

FIG. 8 is a rear elevation view thereof.

The broken line portions of FIGS. 4-8 are included to show unclaimed subject matter only and form no part of the claimed design.
